DESIGN FOR A BOTTLE

Frasier Smith, Wheeling, W. Va., assignor to L. Perrigo Company, Allegan, Mich.

Application October 16, 1947, Serial No. 141,945

Term of patent 14 years

(Cl. D58—6)

To all whom it may concern:

Be it known that I, Frasier Smith, a citizen of the United States, residing at Wheeling, in the county of Ohio and State of West Virginia, have invented a new, original, and ornamental Design for a Bottle, of which the following is a specification, reference being had to the accompanying drawing, forming part thereof.

Figure 1 is a perspective view of a bottle, showing my new design; and

Figure 2 is a front view thereof.

I claim:

The ornamental design for a bottle, as shown.

FRASIER SMITH.
